Primary Examiner — Cynthia Underwood

(57) **CLAIM**

We claim the ornamental design of an ellipsoid wire retention device, as described herein.

DESCRIPTION

FIG. 1 is a perspective view of the ellipsoid wire retention device, the opposite side being a mirror image thereof; FIG. 2 shows a front elevation view, the opposite side being a mirror image thereof; FIG. 3 shows a right side elevation view, the opposite side being a mirror image thereof; and, FIG. 4 shows a top elevation view, the opposite side being a mirror image thereof.
